UNITED STATES PATENT OFFICE.

JUSTUS W. KING AND HENRY N. DRAKE, OF INDEPENDENCE, IOWA.

STEAM-GENERATOR.

SPECIFICATION forming part of Letters Patent No. 225,617, dated March 16, 1880.

Application filed August 11, 1879.

To all whom it may concern:

Be it known that we, JUSTUS W. KING and HENRY N. DRAKE, of Independence, in the county of Buchanan and State of Iowa, have 5 invented certain new and useful Improvements in Steam-Generators; and we do hereby declare the following to be a full, clear, and exact description of the invention, such as will enable others skilled in the art to which it applies to make and use the same, reference being had to the accompanying drawings, and to letters of reference marked thereon, which form a part of this specification.

Our invention relates to a steam-generator, 15 and is designed to provide a construction which will accomplish the general purpose of devices of this character in an effective and improved manner.

In the drawings, Figure 1 is a front perspective view of our steam-generator, looking from above. Fig. 2 is a transverse vertical section of the same.

The fire-box A connects, by the main flue B, with the conical hood C, which latter has 25 its lower portion formed practically in vertical line with the sides of the fire-box. An annular water-space, D, is thereby formed between the fire-box top and the hood-bottom, which subjects the water contained therein to heat on 30 three sides, and is adapted to readily and quickly convert the same into steam. The pipe E, which is coiled within this main flue, communicates with said water-space respectively on opposite sides of the latter, and aids 35 largely in quickly heating the water.

Directly over the main flue, and within the conical hood, is located the water-tank F, which is supported on standards or by other means at a suitable distance from the bottom of the 40 hood, thus permitting the products of combustion to have free draft in their passage upward about the sides of the tank. The size of this tank relative to the hood is such as to form an annular draft-passage, a, between the 45 sides of the two, and from this passage the products of combustion pass over the top of the tank, up through the hood, and finally out of the smoke-exit flue G.

The tank has a vertical feed-opening, a', 50 which passes the water up therein from the

annular water-space below the hood, and its discharge-opening b passes through the side of the hood. The position of the tank is such as to subject it to the direct impact of the products of combustion, and is peculiarly adapted 55 to heat the water contained therein.

The head H of the boiler-cylinder K is seated down within the latter, so as to form the water-feed reservoir L. A water-feed pipe, M, passes from this reservoir a suitable distance down 60 into the boiler. This cylinder-head is formed with the annular air-chamber e, which prevents the condensation of steam against its under side. The steam-discharge N passes through the cylinder-head, and permits the 65 generated steam to be conducted off free from the water. The water from the boiler is discharged, as desired, by the waste-pipe P. A steam-gage cock, R, is connected with the boiler at any desired point. The fire-box is 70 provided with a false bottom, S, loosely supported therein by suitable means, and free to be removed therefrom. A packing or layer of non-combustible material, T, is interposed between said false bottom and the real bottom 75 of the fire-box, and prevents the latter from burning out.

Having fully described our invention, what we claim as new, and desire to secure by Letters Patent, is—

1. In a steam-generator, the combination, with the boiler-cylinder, of the head seated therein, and forming a water-feed reservoir, said head being made with the annular air-chamber and provided with the steam-discharge, substantially as set forth.

2. In a steam-generator, the combination, with conical hood C, fire-box A, and annular water-chamber D, of flue B, coil-pipe E, tank F, annular draft-passage a, and pipes a' b, 90 substantially as set forth.

In testimony that we claim the foregoing we have hereunto set our hands this 16th day of May, 1879.

JUSTUS W. KING.
HENRY N. DRAKE.
